KNOCK-OUT FOR BOX MAKING MACHINE

Elbert Litton Bivans, Glendale, Calif., assignor to E. L. Bivans, Inc., Los Angeles, Calif., a corporation of California

Application March 23, 1953, Serial No. 343,837

6 Claims. (Cl. 93—53)

The invention relates to a box making machine and more particularly to means for ejecting or knocking out a pasteboard box, after the machine has transferred a folded flat box from a magazine or supply station to an operating station where the box is erected and the side flaps folded and the end flap tucked in. This erecting and tucking operation is the only box making operation performed by the machine, as the box is filled and closed by hand or by other means forming no part of the present invention. After the box has been erected and the flaps at one end thereof tucked in, the next step is to advance the box so that a new folded flat box can be transferred from the magazine to the operating station to repeat the process.

While it is possible to eject the finished box by the advance of the next blank, an object of the present invention is to provide a more positive ejection of the finished box without relying on the next blank box to do it.

A further object of the invention is to provide for such more positive ejection of the finished box without interfering with a straight line travel from the supply station to the operating station, the set up box being ejected along this same straight line. The invention provides an ejector which does not extend beyond the tucking and folding mechanism, while providing only one drive for both the fork which feeds the flat box and the ejector which ejects the finished box. This is accomplished by providing a sliding connection between the ejector and the fork, the forward movement of the ejector being stopped at the operating station in advance of the folding and tucking mechanism, while the fork overrides the ejector, the fork moving forward to feed the next flat box to the operating station of the fork, a spring means extends the ejector in front of the fork so that a finished box will be ejected before the next flat box or carton is fed to the folding station.

According to the invention, a separate ejector is provided, this ejector being reciprocated along the bed by the same drive which drives the fork, a spring being employed to urge the ejector above the level of the bed in position to contact the finished box and eject it. The fork is employed to retract the ejector below the level of the bed on arrival of the fork at the operating station with the next blank. The fork thus retracts the ejector after the ejector has been retracted by the next flat box and providing that the carton is short in length, with the ejector in a corresponding advanced position, as illustrated in the drawings.

For further details of the invention reference may be made to the drawings wherein—

Fig. 1 is a plan view of a box making machine having a knock-out according to the present invention, with parts broken away.

Fig. 2 is a sectional view on line 2—2 of Fig. 1.

Fig. 3 is a sectional view on line 3—3 of Fig. 2.

Fig. 4 is a vertical sectional view across the feed device and bed of the machine, with parts broken away.

Fig. 5 is a sectional view on line 5—5 of Fig. 3.

2

Figs. 6, 7 and 9 are sections on lines of the corresponding numbers in Fig. 5.

Fig. 8 is a perspective view showing the box and flap folding devices.

Fig. 10 is a sectional view corresponding to Fig. 9, with the end flap tuckers in another position.

Fig. 11 is a view like Fig. 10 showing the end tuckers in final tucking position.

Fig. 12 is an enlarged sectional view on line 12—12 of Fig. 1.

The same form of end flap tucker is shown in Figs. 9 to 12.

Figs. 13, 14 and 15 are vertical sectional views like Fig. 12 of a modification for tucking the end flap under the front of a shallow box or under the concave front of a box.

Fig. 16 is a perspective view of a box having a concave front and for which the tuckers of Figs. 13, 14 and 15 have been provided.

Fig. 17 is an exploded perspective view of the end tucker of Figs. 13 to 15.

Figs. 18 and 19 are sectional views of a further modification for operating on a shallow box, these figures showing the end tuckers in different positions.

Referring in detail to the drawings, the box making machine comprises a rectangular casing 1 mounted on rollers 2. The casing 1 has a top 3 having a magazine 4 for a stack 17 of collapsed boxes like 5, also a folding station 6 where the collapsed box is expanded to open position and the side flaps 7 and 8, see Fig. 1, and the bottom end flap 9 are tucked in. The box thus opened and tucked ready for ejection is shown in Fig. 11 although the end tuckers would first be moved away from the end of the box.

The box blanks 5 are fed one at a time from the bottom of the stack 17 by means of a fork 18 which rides in an opening 20 in the bed 21 adjusted to fit a given box. The fork 18 has a bracket 150 carried by a runner bar 22, see Fig. 2, bracket 150 being driven through a suitable crank and lever system 23 by a motor 24. The speed of motor 24 can be changed by a controller 25. The drive for the fork 18 is disclosed and claimed in application S. N. 140,073 filed January 23, 1950, for Box Making Machine, now U. S. Patent No. 2,682,209, issued June 29, 1954.

The motor 24 through suitable belts or pulleys as indicated in Fig. 2 drives a pulley 26, see Fig. 2 also Fig. 5, on a countershaft 27 which carries all of the various cams for operating the tucking devices. The shaft 27 is mounted in suitable bearings like 28, 29 carried by the framework 30 of the casing 1. Cam 31, see Figs. 3 and 5, operates the side tuckers 32, 33 in and out, these tuckers being operated by a bell crank 34 having a link 35 connected to a lever 38 having a cam follower 36. The cam follower 36 is urged on the cam 31 by a spring 37. The spring 37 urges the tuckers 32 and 33 out, driving dwell 39 but is not sufficient to retract these tuckers if boxes are jammed at the folding station 6. To overcome this, as shown in Figs. 5 and 7, the cam 31 is provided with an overhang 40 to provide a groove 41 in which the cam follower 36 rides, to positively operate the side tuckers 32 and 33 and permit the ejection of a faulty box so that subsequent operations will be normal without stopping the machine.

As shown in Fig. 3 the side tucker 32 is carried by a slide 42 connected through a link 43 with one side of bell crank 34. The other side tucker 33 not only moves in and out but also up and down, as described and claimed in application S. N. 140,073, filed January 23, 1950, for Box Making Machine, now Patent No. 2,682,209. The side flap tucker 33 as shown in Figs. 3, 6 and 8, is carried by an oscillating arm 50 having a

hinge connection 53 with a slide 55 on rod 56. Slide 55 has a cam follower 51 so that it is raised and lowered by cam 52. Spring 57 urges follower 51 onto cam 52. The side tucker 33 is moved in and out by a link connection 54 with the bell crank 34.

The up and down movement of side tucker 33, by means of cam 52, also serves to swing the side plate 60 between horizontal and vertical positions. Plate 60 is connected to slide 55 by a link 62, see Fig. 6. When the cam 52 raises follower 51 as shown in Fig. 6, this raises not only the side tucker 33, but also swings up the plate 60 to upright position as shown also in Fig. 8. The opposite plate 63 is fixed in upright position and does not move. The plates 60 and 63 have adjustable shelves like 64 for boxes of different depths.

When plate 60 swings up to open the box as shown in Fig. 8, the box is thus gripped or held between the plates 60 and 63 and their shelves like 64, while the various tuckers are operating. The primary and secondary tuckers disclosed herein are disclosed and claimed in application S. N. 209,343, filed February 5, 1951, for Box Making Machine, now U. S. Patent No. 2,682,210, issued June 29, 1954.

As shown in Fig. 8, the side tucker 33 is fixed to the top of arm 50 which also carries a stud 65 serving as a hinge support for a bracket 66 which carries an adjustable presser 67 which offers a resilient abutment against which the end flap 9 is folded by the end tuckers 70. The presser 67 is urged towards the end tucker 70 by a spring 68. The other side tucker 32 has a similar presser 69.

As shown in Figs. 9 to 12, the end tucker 70 is in two parts, of which the part 71 may be designated a primary tucker and the part 72 a secondary tucker. The tucker 71 has a bracket 73 which adjustably carries a curved plate 74 which acts as a guide for the end flap. Plate 74 extends beyond the outer end 75 of the tucker 72 so that guide 74 can move relatively to the tucker 72 to fold the end of flap 9 at its outer fold line 76 as shown in Fig. 10. The hinge axis 77 of both the tuckers 71 and 72 is adjacent and parallel to the inner fold line 78 of the box. The tucker 71 in moving to fold the outer end of the flap as shown in Fig. 1 brings the guide 74 to a position where its outer end 79 is just underneath the top 3 of the box to provide a path leading into the open end of the box, whereby subsequent movement of tucker 72 completes the tucking operation while the guide 74 guides the folded outer end of the flap into the box.

As shown in Fig. 12, in their lowermost positions, the end 79 of tucker 71 and the tucker 72 are horizontal in line with the bed 21 so as to not obstruct the ejection of the finished box.

The bracket 73, as shown in Figs. 9, 10 and 11 rests on an adjustable stop 80 which is adjusted to bring the end of guide 79 to the horizontal position shown in Fig. 12.

The tucker 71 is operated by a cam 81 having a cam follower 82, on a lever 83 connected to a link 84 adjustably connected to bracket 73 as shown at 85 in Fig. 12. The follower 82 is shown above cam 81 in Fig. 9 because the stop 80 is supporting the bracket 73. The tucker 72 has a bracket 86 connected to a link 87 operated by lever 88 having a cam roller 89 for cam 90. The cams 81 and 90 are fixed to the shaft 27. As shaft 27 rotates, cam 81 picks up its roller 82 and its elevated position is shown in dotted lines at 91 where it is resting on the dwell 92 with the parts in the position shown in Fig. 10. In rising, bracket 73 picks up tucker 72 and elevates it to the position shown in Fig. 10 although this elevating could be done by cam 90. As follower 91 reaches the dwell 92, the rise 93 on cam 90 operates the tucker 72 to vertical position shown in Fig. 11 to complete the tucking.

In the form of end tucker shown in Figs. 9 to 11, the guide 74 is concentric with the hinge axis 77, but in some cases, when the box is unfolded to open position, the box front is concave as shown at 100 in Fig. 16. In this case,

the concentric guide 74 would not lead the end of the flap into the box. To overcome this, the guide 101 on the primary tucker is made eccentric with the hinge axis 102 of the tuckers, that is the distance from axis 102 to the inner end 103 of guide 101 is greater than the distance from axis 102 to the outer end 104 of the guide and the latter distance is less than the radius of the secondary tucker 105. The guide 101 has a hinge support on bracket 106.

For example, guide 101 has a plate 107 having an aperture 108 through which extends a stud 109 having a compression spring 110. Plate 107 has apertures 111, 112, see Fig. 17, which loosely fit on pins 113, 114 on a plate 115 adjustably secured on bracket 106 by a screw 116. As shown in Fig. 14, the outer end 104 of guide 101, when the latter is in its elevated position, arrives at a position low enough to enter the uppermost front 100 of the box in position to guide the folded end 117 of the flap into the box as shown in Fig. 15. In so doing, the secondary tucker 105 raises the guide 101 against the action of spring 110, to elevate the concave front 100 for entry of the flap end 117.

Figs. 18 and 19 illustrate a modified form of end tucker for a shallow box 120 having a long end flap 121. In this case, the guide 122 of the primary tucker is provided with a guide portion 123 which extends at an acute angle to the bracket 124. In other words, the distance from the outer end 125 of the guide 123, to the hinge axis 126 of the tuckers is less than in the form shown in Fig. 14 and small enough to fold the end 121 down so that when both the primary tucker 122 and the secondary tucker 128 are later operated as above described, the flap end 121 will be guided into the box by the guide 123.

To adjust the end tuckers for boxes of different dimensions, as will be apparent from various forms in Figs. 12 to 19, the primary tucker or guide like 74 in Fig. 12 may be removed and other sizes or types substituted, and the position of guide 74 on bracket 73 may be adjusted by screw 129. The same thing applies to the primary tuckers shown in the other figures. Also the secondary tucker 72 has a size about the same as the end of the box and various sizes of tucker 72 may be used instead, tucker 72 being removably held on a base 130 by screw like 131. The same applies to the secondary tuckers in the other figures. For various shallow boxes, the plate 72 may be omitted and the support 130 in Fig. 12 then serves as the secondary end tucker. The secondary tucker instead of having a plate like 72, as shown in Figs. 18 and 19, may have a strip 132 fixed to the end of the base 130 by screws like 134. The advantage of this, for a shallow box, is that the base 130 has a rear portion 135 which is on a level with the bed 21 while the outer portion of base 130 and the strip 132 are at a lower level as indicated in 136 in Fig. 18. As the primary guide 122 swings up, the secondary tucker 128, 130 being horizontal, the guide 123 bends the flap 121 over the end of strip 134 with the outer end of the flap 121 closer to the hinge axis 126 and hence in a better position to enter into the box, than would otherwise be the case.

After the end flap 9 has been tucked in, the end tucker like 70 in Fig. 12 is returned to open position so as to not obstruct the ejection of the finished box, the side flap tuckers 32 and 33 are retracted and the plate 60 is swung down to position shown in Fig. 1, ready for the next box blank.

The bottom blank on the stack 17 may be released one at a time by a suitable escapement 137, see Figs. 1 and 3.

If desired, the finished box may be ejected by the next blank which is advanced by fork 18. Preferably, however, the ejector is a separate item from the fork 18. As shown in Figs. 2, 4 and 9, fork 18 is connected with a tube 138 in which slides a rod 139 having an ejector 140 pivotally mounted thereon as indicated at 141. The ejector 140 is in the form of a hollow head urged upwardly by spring 142. The forward movement of ejector 140 is limited by shoulder 156 on rod 139 striking a

rubber bumper 143 on the frame 30 of the machine. Tube 138 has a spring 144, see Fig. 4, which urges ejector 140 forwardly. Runner bar 22 has a bracket 150. Fixed to bracket 150 is a tubular sleeve or bearing 151 which slides on rod 152 fixed to the framework 30 of the machine. Bracket 150 also has a U-shaped bearing 153 which slides on a rectangular bearing member 154 fixed to the frame 30. Bracket 150 has an upright post 155 which carries the tube 138. The flat box 5 is thus fed along the bed 21 from the magazine 4 to the folding station 6 in a certain direction and the ejector 140 ejects the finished box in the same direction, so that the flat carton and the finished box have a straight line of travel in one direction. Also, the fork 18 overrides the ejector 140 when the forward movement of the ejector 140 is restrained by the bumper 143, while the fork continues to advance and bring a new box blank to the folding station 6. The forward position of ejector 140 does not reach or pass the space where the various end and side flap tuckers are arranged at the end of bed 21, whereby these tuckers at times can intercept the path along the bed 21, without interfering with the operation of the ejector 140.

When ejector 140 is at its forward position, it has ejected the finished box, and as fork 18 brings a new blank to the folding station 6, after the box blank 5 has cammed down the ejector 140, the lower front end 145 of fork 18 cams the ejector 140 down by acting on the outer surface 146 of the ejector as shown in Fig. 9. This cam action takes place if the box is short with the fork 18 at a corresponding advanced position on bracket 150 as shown in the drawings. When the fork 18 makes its return stroke, the tube 138 contacts a bumper 157 in front of spring 147 on rod 139 to retract rod 139 and the ejector 140. Spring 147 has a stop 158 fixed to rod 139.

Various modifications may be made in the invention without departing from the spirit of the following claims.

I claim:

1. A box making machine comprising a supply station for a stack of flat folded boxes each having an end flap and side flaps, an operating station comprising means for erecting the box and means for tucking the end and side flaps of the erected box, a bed between said stations, a reciprocating fork movable along said bed for transferring a flat box from said supply station to said operating station, a reciprocating ejector movable along said bed for ejecting the open tucked box from said operating station, a spring urging said ejector above said bed, said fork being engageable with said ejector after said fork has been depressed by the oncoming box, to hold said ejector depressed below said bed on arrival of said fork at said operating station to prevent said fork from exerting pressure on said box.

2. A box making machine comprising a bed, a reciprocating fork movable along said bed, said fork having a tube, a rod slidable in said tube, said rod having a front end having a pivoted ejector, a spring urging said ejector above said bed, a spring in said tube acting on said tube and said rod and urging said ejector forwardly ahead of said fork, a stop limiting forward movement of said 60 ejector during advance of said fork, said rod having a

rear end having an abutment engageable by said tube for retracting said ejector along said bed and a reciprocating drive for said fork.

3. A box folding machine comprising a supply station for supplying a stack of flat folded boxes each having end and side flaps, a folding station, a bed providing a box path from said supply station to said folding station, a fork for conveying a flat box from said supply station to said folding station endwise in a horizontal position in a certain direction, said folding station comprising means for setting up the box in horizontal position, said folding station also comprising separate means for folding said side flaps and tucking said end flap into the box, and means for thereafter ejecting the tucked box from said folding station endwise in the same direction, said fork having an overriding connection with said ejecting means with spring means urging said ejector ahead of said fork, means for stopping the travel of said ejecting means at said folding station in advance of said folding means and said tucking means during advance of said fork, and means yieldably urging said ejecting means in said path in position to engage the tucked box at said folding station.

4. A box folding machine according to claim 3 comprising means on said fork engageable with said ejecting means to move said ejecting means out of said path when said ejecting means is stopped by said stopping means, after said fork has been depressed by the oncoming box, to hold said ejector depressed below said bed on arrival 30 of said fork at said operating station to prevent said fork from exerting pressure on said box.

5. A box machine comprising a bed for boxes, a reciprocating member, a fork for said bed, an ejector for said bed, said member having a driving connection with both said fork and said ejector, said fork having an overriding connection with said ejector with spring means urging said ejector ahead of said fork, means for stopping travel of said ejector during forward movement of said fork, and means yieldably urging said ejector above said bed.

6. A box folding machine comprising a supply station for supplying a stack of boxes each having a flap, a folding station, a bed providing a box path from said supply station to said folding station, a fork for conveying a box from said supply station to said folding station in a certain direction, said folding station comprising means for folding said side flap, and means for thereafter ejecting the box from said folding station in the same direction, said fork having an overriding connection with said ejecting means with spring means urging said ejector ahead of said fork, means for stopping the travel of said ejecting means at said folding station in advance of said folding means during advance of said fork, and means yieldably urging said ejecting means in said path in position to engage, at said folding station, the box acted on by said folding means.
